US00D384549S

United States Patent [19]

Cesaroni et al.

[11] Patent Number: Des. 384,549

[45] Date of Patent: **Oct. 7, 1997

[54] ELECTRONIC STAND MIXER

[75] Inventors: William C. Cesaroni, Glenview, Ill.; William C. Dobson, West Bend, Wis.

[73] Assignee: The West Bend Company, West Bend, Wis.

[**] Term: 14 Years

[21] Appl. No.: 53,162

[22] Filed: Apr. 15, 1996

[51] LOC (6) Cl. 31-00

[52] U.S. Cl. D7/379

[58] Field of Search D7/376-379, 412; 366/129, 130, 142, 197, 199, 204, 205, 279, 314
